CLAIM

I claim the ornamental design for a bicycle hub body, as shown and described.

DESCRIPTION

FIG. 1 is a top, front and left side perspective view of a bicycle hub body.

FIG. 2 is a top, front and left side perspective view of a bicycle hub body.

FIG. 3 is a front elevational view of a bicycle hub body.

FIG. 4 is a rear elevational view of a bicycle hub body; and, FIG. 5 is a left side elevational view of a bicycle hub body, the right side elevational view, top and bottom plan views being identical.

The broken lines in the drawings represent bicycle wheel and spoke elements that form no part of the claimed design.
